UNITED STATES PATENT OFFICE

147,533

DESIGN FOR A COMBINED ELECTRIC LAMPSTAND AND CLOCK

Donald Walter Alexander Cameron, Musbury,
Axminster, England

Application May 7, 1946, Serial No. 129,407
In Great Britain March 15, 1946

Term of patent 14 years

(Cl. D48—20)

To all whom it may concern:

Be it known that I, Donald Walter Alexander Cameron, a subject of the King of Great Britain, of "Rumah Kita," Musbury, Axminster, in the county of Devon, England, have invented a new, original, and ornamental Design for a Combined Electric Lampstand and Clock, of which the following is a specification, reference being had to the accompanying drawing, forming part thereof.

In the accompanying drawing:

Figure 1 is a front perspective view of a combined electric lampstand and clock, showing my new design; and

Figure 2 is a rear perspective view of the same.

I claim:

The ornamental design for a combined electric lampstand and clock, as shown.

DONALD WALTER ALEXANDER CAMERON.
